SHOCK RESISTANT CONTAINER

John Kearsley M. Harrison, Gainesville, Va.

Application June 24, 1947, Serial No. 756,662

8 Claims. (Cl. 229—5.5)

1

This invention relates to containers and particularly to nonmetallic containers of the type used for the packaging of liquids such as oils or foodstuff.

In the design of containers made of plastic, paper or other nonmetallic material the principal problems presented are the maintenance of an adequate cost margin over metal containers together with the attainment of such objectives as mechanical strength, adequate resistance against leakage of liquid from the container, adequate resistance against leakage of moisture into the container, and ease of access to the container contents.

Toward the attainment of the foregoing objectives much effort has been expended and many forms of paper containers are now available in competition with metal containers of like capacity. With the advent of new liquid-proof plastic materials, the problem of leakage through the walls of nonmetallic containers has been to a large extent solved. However, the problem of mechanical strength has not been heretofore solved in any inexpensive manner which is consistent with commercial requirements regarding resistance to leakage at the seams between the end closures and the remainder of the container.

It is therefore an object of this invention to provide a nonmetallic container for the shipment and storage of liquid materials which is characterized by a simple and inexpensive type of construction which is very resistant to mechanical shock and which wholly prevents out-leakage of the contents of the container and in-leakage to those contents while affording a closure which may be easily broken when desired to gain access to the contents of the container.

It is contemplated, according to this invention, to provide a nonmetallic container having an end structure characterized by a flexible portion and a rigid portion coacting to provide adequate seals and high resistance to rupture incident to rough handling or other mechanical strain.

Other objects and advantages of the invention will be apparent upon consideration of the following detailed description of a preferred embodiment thereof in conjunction with the annexed drawings wherein:

Figure 1 is a view in vertical section of one end of a cylindrical container constructed in accordance with the teachings of the present invention; and

Figure 2 is a view partially in vertical section and partially in elevation illustrating one of the steps in an assembly of a container of the type shown in Figure 1.

Now referring to Figure 1 in greater detail, the container consists of a cylindrical body portion 10 of which only the upper portion is shown in the drawing. It is contemplated that the

2

lower or unshown end of the container will be provided with a closure either of the type shown in conjunction with the top closure in Figure 1, or of some other type known to the art.

The upper closure for the body portion 10, which is shown in Figure 1, is comprised of a flexible disc 11 of laminated parchment, cellophane, or the like having an integral annular flange 12 extending toward the end of the container, a rigid closure disc 13 and a rigid cover disc 14.

The flexible closure disc 11 has an over-all area in excess of the cross sectional area of the container body at the plane *a*—*b* indicated in the drawing, so that the disc 11 may flex in response to pressure differences thereacross. The disc 11 is inserted in the cylindrical body 10 in the manner shown in Figure 2. An annular zone 14 adjacent the end of the cylindrical body 10 is coated with a suitable adhesive and then the disc 11 is forced through a dye 15 by a plunger 16 and is pushed to the position indicated in Figure 1. The plunger deforms the marginal portions of the disc 11 to form the flange 12 and likewise displaces the adhesive to form an annular sealing fillet at 17, see Figure 1. It should be noted that the end of the plunger 16 is convex so that the portion of the disc 11 which extends across the container body will have an area slightly in excess of the cross sectional area of the body.

From the foregoing it can be seen that the disc 11 is held in position by the adhesive and is put into position as the first step in effecting the enclosure. After the disc 11 has been placed in position a rigid closure disc 13 is inserted and this disc is wedged in overlying relation to the flange 12 of the disc 11. The disc 13 is slightly frusto conical and is inserted with its face of minimum diameter extending inwardly toward the center of the container. As it is pushed into place its margin exerts a wedging action on the flange 12 and serves to supplement the adhesive in holding that flange against the wall of the container. After the disc 13 is in position, the end of the container is spun over at 18 to hold the disc 13 in position. In view of the fact that forcing the disc 14 in position might create sufficient air pressure to rupture the disc 11, disc 13 is provided with a vent aperture at 19 so that air trapped between the discs 11 and 13 during the insertion of the disc 13 is permitted to escape.

After the disc 13 has been placed in position and the spun over portions 18 have been formed, a waterproof cover disc 14 is wedged in position overlying the disc 13 and is held marginally by the spun over portion 18. The disc 14 is impregnated with a waterproofing material and forms with the spun over portions 18 a very tight fit at annular zone 20. This fit, together with the

waterproofing character of the disc 14, prevents contamination of the contents of the container by in-leaking water. Out-leakage of the contents of the container is prevented by the disc 11 and the sealing fillet 17. If the container is dropped or otherwise subjected to rough handling, the gas trapped in the space between the flexible disc 11 and the rigid disc 13 is compressed momentarily to act as a resilient cushion preventing permanent displacement of the rigid parts of the end closure and protecting the container against shock damage.

While the invention has been described with respect to but a single embodiment thereof, it is apparent that various changes and modifications of the construction are possible within the scope of the invention as defined by the appended claims.

What is claimed is:

1. A container having a flexible imperforate closure adjacent an end thereof, said closure having an integral flange extending toward said end of the container, sealing means bonding said flange to the container wall, and a plane rigid closure spaced within said flange between said end of the container and said flexible closure and being in spaced relation to said flexible closure and held in position by a deformed portion of the container.

2. A cylindrical container having a flexible imperforate closure disc adjacent an end thereof, said closure having an integral annular flange extending toward said end of the container, sealing means bonding said flange to the inner wall of the container, and a plane rigid closure disc spaced between said end of the container and said flexible closure disc and being in spaced relation to said flexible closure and held in position by a deformed portion of the container, said rigid disc being frusto conical in contour with its base surface facing outwardly of the container and its edge bearing against said flange.

3. A container having a flexible imperforate closure adjacent an end thereof, said closure having an integral flange extending toward said end of the container, sealing means bonding said flange to the container wall, a plane rigid closure spaced between said end of the container and said flexible closure and being in spaced relation to said flexible closure and held in position by a deformed portion of the container, said rigid closure having a vent aperture therein and a rigid cover member overlying the outer surface of the rigid closure member and covering said vent, said cover member being frictionally held against the deformed portion of the container and the margin of said rigid closure bearing against said flange.

4. A cylindrical container having a flexible imperforate closure disc adjacent an end thereof, said disc having an integral flange extending toward said end of the container, sealing means bonding said flange to the container wall, a plane rigid closure disc spaced between said end of the container and said flexible closure disc and being in spaced relation to said flexible closure and held in position by a deformed portion of the container, said rigid disc having a vent aperture therein and a rigid cover disc overlying the outer surface of the rigid closure disc and covering said

vent, said cover disc being frictionally held against the deformed portion of the container and the margin of said rigid closure disc bearing against said flange.

5. A cylindrical container having a flexible imperforate closure disc adjacent an end thereof, said closure having an integral flange extending toward said end of the container, sealing means bonding said flange to the container wall, the area of said disc being greater than the cross sectional area of the container at the plane of the disc and a plane rigid closure disc spaced between said end of the container and said flexible closure and being in spaced relation to said flexible closure and held in position by a spun over portion of the container.

6. A cylindrical container having a closure disc of flexible imperforate parchment adjacent one end thereof, said closure having an integral annular flange extending toward said end of the container, sealing means bonding said flange to said container and defining an annular fillet at the margin of the closure disc extending in a direction opposite to the direction of the flange, a plane rigid closure disc marginally engaging the flange of the parchment disc and lying between said parchment disc and said end of the container and being in spaced relation to said parchment disc, a spun over portion of the container serving to hold said rigid disc in position, said rigid disc having a vent aperture therein and a rigid cover disc marginally bearing against said spun over portion and having a face bearing against the outer face of said rigid closure disc.

35 7. A cylindrical container as claimed in claim 2 further characterized by said flexible imperforate closure disc being made of cellophane.

8. A cylindrical container having a flexible imperforate closure disc adjacent an end thereof, said closure having an integral annular flange extending toward said end of the container, said closure having an over-all area in excess of the cross-sectional area of the said container, sealing means bonding said flange to the inner wall of the container, and a plane rigid closure disc spaced between said end of the container and said flexible closure disc and being in spaced relation to said flexible closure disc and held in position by a deformed portion of the container, said rigid disc being frusto conical in contour with its base surface facing outwardly of the container and its edge bearing against said flange.
